UNITED STATES PATENT OFFICE.

WILLIAM H. V. SHRUM, OF COLUMBUS, OHIO.

Boomerang.

1,245,279.

Specification of Letters Patent. Patented Nov. 6, 1917.

Application filed August 7, 1916. Serial No. 113,628.

To all whom it may concern:

Be it known that I, WILLIAM H. V. SHRUM, a citizen of the United States, residing at Columbus, in the county of Franklin and State of Ohio, have invented certain new and useful Improvements in Boomerangs, of which the following is a specification.

This invention relates to an instrument commonly known as a boomerang, wherein considerable skill of the operator is necessary to make the instrument properly sail through the air and return.

The main object of this invention resides in the peculiar shape of wings or vanes constituting the boomerang, necessary to make it perform various functions in sailing through the air when properly thrown. Primarily, the invention consists in making the vanes of a longitudinal undulatory form representing a flattened S, more or less. By means of this shape, the air is cleaved to a greater extent, thereby making the instrument soar to a higher level when thrown in one manner or making it sail in a shorter circular path when thrown in another manner. In addition, the arrangement may be such as to cause a combining of the two as related.

A further object of this invention resides in operatively mounting a plurality of boomerang vanes in connection with a base unit, thereby causing this base unit to soar through the air when the instrument, as a whole, is properly thrown. By the use of a base unit, I do not mean one of the boomerang vanes itself, but what may be termed an extraneous unit, which may be made to assume various shapes, such as, fishes, fowl, etc.

Still a further object of the invention resides in rotatably mounting a spinner structure in connection with the boomerang instrument, whereby a rotation of this spinner structure independent of the rotary movement of the boomerang may be had when properly thrown. This is particularly useful in producing various effects, for instance, by performers upon the stage and, likewise, the various preceding objects may also be utilized to marked advantage when the instrument is put to such use. Also, this latter, as well as the various other features, may be put to commercial use when the instrument is used as a toy.

Various other features reside in the novel construction employed as are shown in the

accompanying sheet of drawings, wherein similar characters of reference designate corresponding parts and wherein:

Figure 1 is a view showing one form to which my invention may be put,

Fig. 2 is an enlarged cross section taken through a portion of the structure shown in Fig. 1,

Fig. 3 is an enlarged section taken on line 3-3 of Fig. 1, and,

Figs. 4, 5 and 6 are detail cross sectional views taken through one of the vanes as represented on corresponding lines in Fig. 2.

In these drawings, I have shown a base unit 1 in the shape of a fish, although it may be understood that this base unit may be of any appropriate size or shape. For purposes of lightness, this base unit is also concaved on its underside, as is shown at 2 in Fig. 2, although this concavity is not absolutely necessary, since the boomerang wings may be made of a size sufficient to support the base unit through the air, if so desired. Further, I have shown this base unit as being provided with a pair of boomerang vanes 3, which vanes are pivotally connected to the base unit at 4. The particular shape of these vanes forms the very essence of this invention and reference to Fig. 2 will show that they are shaped longitudinally to assume an undulating form or, in other words, this shape resembles what may be termed a flattened S. In addition, the outer ends 5 of these vanes are bent downwardly to a slight extent to be at a lower level than the intermediate portions 6. The shape of these wings is made in this manner to facilitate a more rapid elevation when thrown in a horizontal plane and to cause their circle of rotation to be somewhat contracted when thrown in a vertical plane, inasmuch as the air must be cleaved to a greater extent.

Preferably, the cleaving edge of each vane is slightly beveled, as is shown at 7, to reduce the amount of resistance. To further enhance their soaring properties, these vanes are warped so that the transverse axes along the lines 6-6 are disposed at a considerable angle to the corresponding axes on the lines 5-5 or 4-4. The advantage of this will be seen by referring to Figs. 4 to 6 inclusive, in which Fig. 4 shows a greater effective surface exposed to the atmosphere, which will naturally cause a greater rising or a circling in a smaller circle depending upon the manner in which the instrument is thrown. Each

of the vanes is provided with a sharp edge to

cause a cutting or cleaving action to

cause a greater rise or a circling in a smaller circle depending upon the manner in which the instrument is thrown. Each

of these vanes, as has been stated, is pivotally mounted as at 4, although the particular location is not essential. In order to hold these vanes in any position of adjustment, I have provided the cord shown at 8, this cord passing through the ends of each of the vanes and through the mouth portion of the fish, to be securely tied at the tail portion of the fish, as is shown at 9. It will thus be seen that the vanes may be rigidly secured in the desired position of adjustment and because of the various positions, the path of travel of the instrument, as a whole, will be correspondingly varied.

In order to further enhance the soaring properties of the instrument, one edge of each of the vanes is straight through substantially its entire length, while the opposite edge is formed to a compound curve, so that the intermediate portion 6 is preferably wider than the outer end portions 5 or the inner portions. For purposes of clearness, I have called the edges 10 the front edges, inasmuch as they are the ones which cleave the air, and the edges 11, rear edges. Because of the greater surface at the warped intermediate portion 6, the instrument is given additional soaring properties, and to reduce their weight, their under surfaces have also been concaved, as is shown at 12, although this latter is not absolutely essential.

In order to make the instrument more unique, I have provided it with an additional element, which I have termed a spinner and which is designated by the reference numeral 13, this spinner being preferably mounted upon the pivot bolt structure and being rotatable independently of the rotation of the instrument as a whole. It will be noted that the wings of this spinner are warped to some extent, to offer resistance to the air and, therefore, the rotation of the spinner will naturally be in a direction opposite from the rotation of the instrument, as a whole, when it is thrown. However, additional means are provided for causing this rotation which may be in the opposite, or in the same direction as the rotation of the instrument as a whole, as may be desired. By referring to Fig. 3, it will be noted that the bolt structure comprises a hollow thimble 14 open at both ends and onto which the thimble 15 is secured. This thimble 15 abuts at one end against the shoulder 16 on the interior thimble and is itself provided with a shoulder 17 at its lower end. At its upper end it is provided with a nut 18 and by means of this nut 18 and the shoulder 17, the two vanes 3 and the base unit 1 are clamped in position. Against each opposite end of this shoulder 17, there are located a pair of washers 19 and against these the spinner 13 rests. This spinner is mounted to loosely rotate upon the thimble 16 and is

70 prevented from dropping therefrom by means of the nut 20 and lower washer 21. The base unit 1 is provided with an arched member 22 which is rigidly secured thereto and similarly the spinner 13 has rigidly connected therewith an arch member 23. A flexible member such as a rubber band 24 is rigidly secured to both these arch members and twisted so that upon release, it supplies energy to cause a rotation of the spinner. 75 This may be utilized to obtain various effects and its value will be particularly apparent to those using the instrument as an act upon the stage.

75 From the foregoing description, it will be apparent that I have provided an instrument which may be made to perform various feats. By means of the shape of the vanes, the distance the instrument will fly and the height to which it will soar, may be 80 varied as desired. Likewise, this same regulation may be obtained by the adjustment of the vanes to, for instance, their dotted line 85 position of Fig. 1, in which position they may be held by suitably securing the cord 8 in 90 position. Likewise, a unique effect may be obtained by means of the spinner shown at 13.

What I claim, is:

1. An instrument of the character described comprising a plurality of vanes disposed at an angle to each other, said vanes being shaped longitudinally to a curve resembling a flattened S. 95

2. An instrument of the character described comprising a plurality of vanes disposed at an angle to each other, said vanes having a longitudinal undulating shape with their outer ends bent down to a lower level than their immediate preceding portion. 100

105 3. An instrument of the character described comprising a plurality of vanes disposed at an angle to each other, said vanes having a longitudinal undulating shape with their outer ends bent down to a lower level, than their immediate preceding portion, said vanes being also warped so that the transverse axis of the outer portion will be inclined to the corresponding axis of the inner portion. 110

115 4. An instrument of the character described comprising a plurality of vanes disposed at an angle to each other, said vanes having straight rear edges throughout substantially their lengths, and curved front edges of compound form, said vanes being of a length to present an elongated intermediate portion wider than the inner or outer ends. 120

125 5. An instrument of the character described comprising a plurality of vanes disposed at an angle to each other, said vanes having straight rear edges throughout substantially their lengths and curved front edges of compound form to present an elong- 130

gated intermediate portion wider than the inner or outer ends, said vanes having a longitudinal undulating shape with their outer ends bent down to a lower level than the

5 intermediate preceding portions and also warped so that the transverse axes of their outer portions will be inclined to the corresponding axis of the intermediate portion.

6. An instrument of the character de-
10 scribed comprising a plurality of vanes dis-
posed at an angle to each other, said vanes
having a longitudinal undulating shape with
straight rear edges throughout substantially
15 their lengths and curved front edges of com-
pound form to make the intermediate por-
tions wider than the inner and outer ends.

7. An instrument of the character de-
scribed comprising a base unit, a plurality
20 of boomerang vanes attached to said unit to
make it fly when the instrument is properly
thrown, and means whereby said vanes may
be adjusted to various positions with respect
to said unit.

8. An instrument of the character de-
scribed comprising a base unit, a plurality
25 of boomerang vanes pivotally attached by
their ends to said unit to make it fly when
the instrument is properly thrown, and
means for holding said vanes in their ad-
30 justed positions with respect to said unit.

9. An instrument of the character de-

scribed comprising a plurality of boomerang
vanes disposed at an angle to each other,
and a spinner rotatably mounted in connec-
tion with said vanes.

35

10. An instrument of the character de-
scribed comprising a plurality of boomerang
vanes disposed at an angle to each other, a
spinner rotatably mounted in connection
with said vanes, and means for making said
40 spinner rotate independently of the rotation
caused by the throwing of the instrument
as a whole.

11. An instrument of the character de-
scribed comprising a plurality of boomerang
vanes disposed at an angle to each other, a
hollow bolt structure for holding said vanes
45 together, a spinner rotatably mounted in
connection with said bolt structure, and a
flexible member operatively connected to
said vanes at one end and to said spinner
50 at its other end and passing through said
hollow bolt structure so that when twisted
and released it will cause rotation of said
spinner.

In testimony whereof I affix my signature
in presence of two witnesses.
